UNITED STATES PATENT OFFICE

WILLIAM A. FEIGEL, OF BOSTON, AND ROBERT R. CARVER, OF CAMBRIDGE, MASSACHUSETTS, ASSIGNORS TO UNION SPECIAL MACHINE COMPANY, OF CHICAGO, ILLINOIS, A CORPORATION OF ILLINOIS

PANTS BAND SEWING MACHINE

Application filed October 24, 1928. Serial No. 314,700.

The invention relates to new and useful improvements in sewing machines and more particularly to a sewing machine for joining a formed pant band to the body portion of trousers.

An object of the invention is to provide a machine of the above type with means for guiding a body fabric and means for guiding a prefolded stitched pant band so that the folded edge of the lining of the pant band will be laid on top of the body fabric while the stiffening strip of the pant band is laid underneath the body fabric whereby a zigzag stitching mechanism may be utilized for forming stitches alternately passing through the folded edge of the lining and over the edge thereof, and also through the stiffening strip and body fabric for joining the parts.

20 A further object of the invention is to provide a machine of the above type with a guiding means for the formed pant band which has complete control of the lining strip so as to direct the same smoothly to the machine.

25 A further object of the invention is to provide a machine of the above type wherein the guide for the formed pant band is also provided with means for folding the edge of the lining strip.

30 A still further object of the invention is to provide a machine of the above type with a guide for the formed pant band having an adjustable member for varying the width of the guiding channel.

These and other objects will in part be obvious and will in part be hereinafter more fully disclosed.

In the drawings:—

35 Fig. 1 is a front view of a portion of the machine embodying the improvements.

Fig. 2 is an end view of the same.

40 Fig. 3 is a plan view of the work support, pressure foot and guides used in the machine.

Fig. 4 is a sectional view on the line 4—4 of Fig. 3.

45 Fig. 5 is a perspective view of the formed pant band and body fabric showing the manner of guiding the same to the stitching

mechanism, the placing of the parts, and the stitching thereof.

Fig. 6 is a perspective view of the article as completed on the machine.

Fig. 7 is a sectional view showing the parts 55 folded in the manner in which they are used in the completed garment.

Fig. 8 is a view of a portion of the work support, the presser foot, and the guides showing a modified form of guiding device 60 for the formed pant band.

Fig. 9 is a sectional view through the guide for the formed pant band taken longitudinally thereof on the line 9—9.

Fig. 10 is a plan view of the formed pant 65 band and the body fabric showing the manner of interfolding the same by the guiding mechanism shown in Figs. 8 and 9.

The invention is directed to a sewing machine for joining a formed pant band to the 70 body portions of trousers by a single line of zigzag stitches so that the pant band may be secured to the garment by a single operation.

The formed pant band consists of a lining strip and a stiffening strip which are joined by 75 through and through stitches after which the lining strip is folded around onto the other face of the stiffening strip. In certain forms of the invention this lining strip at its free edge is folded so that the fold therein lies 80

along the edge portion of the stiffening strip but back from the edge thereof. It is desired to stitch this formed pant band to the body portion of trousers so that the body portion will lie between the lining strip and the 85

stiffening strip and be so positioned therebetween that a line of zigzag stitches may be passed alternately into the lining strip adjacent the edge thereof and over the edge of the lining strip. These zigzag stitches pass 90

through the body fabric and are completely embedded therein and also through the stiffening strip back from the edge thereof and are completely embedded therein. This produces a joining of the formed pant band to 95

the body portion of the trousers by stitching which closely resembles a hand whip stitch, which joins an edge portion to a fabric and partly covers and ornaments the edge of the strip.

The machine for carrying out the invention includes a zigzag stitching mechanism of the usual type. There is a guide for the body fabric which guides said body fabric so that the needle will penetrate the body fabric at each stitch. This guide for the body fabric is shaped so as to provide a guiding space beneath the same for the stiffening strip of the pant band. Associated with this guiding member for the body fabric is a guiding member for the formed pant band. This guiding member in one form of the invention is provided with a channel which receives the facing strip with the edge thereof folded. The guiding member extends the full width of the facing strip to the fold therein so that the facing strip is controlled and smoothly directed to the stitching mechanism. At the outer edge of the guide for the pant band there is an opening on the under face thereof and also a guiding wall which directs the stiffening strip entirely beneath the guiding member for the facing strip, although these parts are stitched together at the extreme outer edge thereof. This stiffening strip can thus be led underneath the guiding member for the body fabric. The guide is so positioned relative to the stitching mechanism that the zigzag stitches will pass alternately into and out of the edge of the facing strip and through the body fabric and stiffening strip at each stitch.

In another form of the invention the guide for the facing strip is provided with means for infolding the edge of the facing strip and also with means which is adjustable for varying the capacity of the guide for different widths of pant bands.

Referring more in detail to the drawings, the invention is shown as applied to a sewing machine having a work support 1 and an overhanging arm 2 on which is mounted a needle gate 3. A needle bar 4 is mounted for reciprocation in the needle gate and is actuated by means of a needle lever 5 connected to the needle bar by a link 6. The needle bar is provided with a needle 7. Cooperating with this needle beneath the work support is the usual form of complementary stitch forming mechanism. The needle gate is vibrated by means of a link 8 connected to a rock shaft 9 in the usual manner. The material is held on the work support by a presser foot 10 which is likewise of the usual construction.

Mounted on the work support 1 is a guiding member 11 for the body fabric. This guiding member is secured to the work support by means of a screw 12. The right hand portion of this guiding member, as viewed in Fig. 1, is raised so as to provide a space 13. The extreme right hand edge portion of the guiding member at the receiving side thereof is bent upwardly at right angles to form a

vertical guiding wall 14. This vertical guiding wall 14 gradually decreases in height, as shown in Fig. 2, until it finally vanishes in front of the presser foot. The body fabric is indicated in broken lines at B.

Associated with this edge guide for the body fabric is a guiding member for the formed pant band. This guiding member consists of a top plate 15 and a lower plate 16 which are joined by an integral portion 17 at the left hand side thereof as viewed in Fig. 1. Between these plates is a channel 18 through which the facing strip F of the pant band is directed. The plate 15 is bent downwardly at 19. This downwardly bent portion is spaced from the right hand edge of the plate 16 so that the channel 18 extends around the edge of the plate 16 and beneath said plate. The downwardly bent portion 19 is extended as indicated at 19a underneath and downwardly relative to the plate 16. The stiffening strip is indicated at S in the drawings. The stiffening strip and the facing strip are joined by a line of stitching s. This is done before the pant band is brought to the machine for stitching it to the body fabric. After these parts are joined, then the facing strip is folded around onto the opposite face of the stiffening strip and this forms the pant band which is to be attached to the body fabric of the trousers.

As shown in Figs. 1 to 5 the facing strip F has its edge portion folded underneath as indicated at f. This fold is formed in the facing strip prior to the insertion of the strip in the guide so that the strip with the folded edge portion passes through the channel 18. The stiffening strip S passes underneath the plate 16 and also underneath the guide plate 11. The space 13 is provided to receive the edge portion of the stiffening strip and this allows the stiffening strip to run freely underneath this guiding member for the body fabric.

The parts of the pant band, positioned as described, are fed through this guiding member and directed to the stitching mechanism. As clearly shown in Fig. 5 of the drawings, the body fabric and the formed pant band are directed to the stitching mechanism so that the needle will penetrate the facing strip at the points p and will then pass over the edge of the facing strip and penetrate the body fabric at the point p'. The needle thread is indicated at n in the drawings. It will be noted that this needle thread between stitches is thus laid across the folded edge of the facing strip and a stitch thus formed which has the appearance of a hand whip stitch. The body fabric extends well in between the facing strip and the stiffening strip so that all the needle punctures are made through the body fabric and also through the stiffening strip. Thus it is that the pant band is secured to the body fabric

with the body fabric lying between the facing strip and the stiffening strip.

In the completed article the body fabric is folded over the edge portion S' of the stiffening strip as shown in Fig. 7. The distance that the stitches are located below this fold in the body fabric depends upon the position of the stitches in the stiffening strip and, therefore, it is quite essential that the 10 stitches shall be a predetermined distance from the edge of the stiffening strip. The edge of the plate 16 lying between the facing strip and the stiffening strip at the extreme right hand edge portion of the pant band co- 15 operating with the portion 17 joining the top plate 15 and said guide plate 16 will guide the pant band so as to properly position the stiffening strip relative to the body fabric and the folded edge of the facing strip.

In Figs. 8, 9, and 10, there is shown a slightly modified form of guiding means for the formed pant band. In this form of the invention the upper plate 15 of the guide for the pant band is bent downwardly and inwardly and upwardly so as to provide a folding scroll 20 which overturns the edge portion of the facing strip. The plate 16 is secured to the underneath portion of the folding scroll 20. The plate 15 at the right hand side of the guide for the pant band is bent downwardly and underneath the plate 16 as indicated at 21. An extension 22 is carried by this member 21. Located between the portion 21 and the portion 15 of the guiding plates is an adjustable edge guiding portion 23 which is held in place by suitable screws 24, 24 passing through slots 25, 25 in the plate 15. The operation of this guide is similar to that described above with the additional feature that the edge of the facing strip is underfolded as it passes through the guide. The advantage of this underfolding of the edge portion of the facing strip is that the fold will be properly positioned relative to the 40 stitching mechanism so as to insure that the edge of the fold will pass between the extreme throws of the needle as it is moved back and forth to form the zigzag stitching. By adjusting the guide for the outer edge 45 portion of the formed pant band, the capacity of the guide may be readily changed for different widths of pant bands. This guide is secured to the work support by suitable screws 26, 26.

From the above it will be apparent that a machine has been provided with means for directing a body fabric and also a formed pant band so that they will be properly positioned and directed to a stitching mechanism whereby a line of zigzag stitches may be passed through the body fabric and stiffening strip and alternately through and over the edge of the facing strip. Thus it is that the formed pant band may be secured to the body fabric of the trousers at a single opera-

tion. These pant bands may be made in long strips and fed to the machine from a suitable source of supply so that the operator is only obliged to give attention to the guiding and directing of the body fabric of the trousers. 70

It is obvious that minor changes in the details of construction and arrangement of the parts may be made without departing from the spirit of the invention as set forth in the appended claims. 75

Having fully described our invention, what we claim as new and desire to secure by Letters Patent, is:—

1. In a sewing machine a stitch forming mechanism for forming zigzag stitches, a 80 guide for guiding a body fabric to the stitching mechanism so that the needle at each stitch enters the body fabric, a guide for guiding a formed pant band so that a folded edge portion of the facing strip is laid on top of the body fabric with the edge thereof within the limits of the zigzag stitching and so that the stiffening strip is laid beneath the body fabric, whereby the needle at each puncture passes through the stiffening strip, 85 said guide for the pant band being provided with means for underfolding the edge of the facing strip as it is led to the stitching mechanism, said guide for the pant band having means for positioning said stiffening strip 90 so that the stitches will penetrate the same at a predetermined distance from the edge thereof. 95

2. In a sewing machine a stitch forming mechanism for forming zigzag stitches, a 100 guide for guiding a body fabric to the stitching mechanism so that the needle at each stitch enters the body fabric, a guide for guiding a formed pant band so that a folded edge portion of the facing strip is laid on top of the body fabric with the edge thereof within the limits of the zigzag stitching and so that the stiffening strip is laid beneath the body fabric, whereby the needle at each puncture passes through the stiffening strip, 105 said guide for the pant band being provided with means for underfolding the edge of the facing strip as it is led to the stitching mechanism, said guide for the pant band having means for positioning said stiffening strip 110 so that the stitches will penetrate the same at a predetermined distance from the edge thereof, said guide for the pant band being also provided with adjustable means for varying the capacity of the guide for pant bands of different widths without varying the position of the guide relative to the work support. 115

3. In a sewing machine, a stitch forming mechanism for forming zigzag stitches, a 125 guide for guiding a body fabric to the stitching mechanism so that the needle at each stitch enters the body fabric, a guide for guiding a pants band so that a folded edge portion of the facing strip is laid on top of 120

the body fabric with the edge thereof within
the limits of the zigzag stitching and so that
the stiffening strip is laid beneath the body
fabric, whereby the needle at each puncture
5 passes through the stiffening strip, said guide
for the pants band being provided with means
for positioning said stiffening strip so that
the stitches will penetrate the same at a pre-
determined distance from the edge thereof.

10 In testimony whereof, we affix our signa-
tures.

WILLIAM A. FEIGEL.
ROBERT R. CARVER.
